UNITED STATES PATENT OFFICE.

EMMA E. HODSON, OF CHICAGO, ILLINOIS.

BUSTLE.

SPECIFICATION forming part of Letters Patent No. 329,042, dated October 27, 1885.

Application filed April 28, 1885. Serial No. 163,750. (No model.)

To all whom it may concern:

Be it known that I, EMMA E. HODSON, a citizen of the United States, residing at Chicago, in the county of Cook and State of Illinois, 5 have invented certain new and useful Improvements in Bustles; and I do hereby declare the following to be a full, clear, and exact description of the invention, such as will enable others skilled in the art to which it appertains to 10 make and use the same.

My invention relates to that class of bustles which are provided with pockets or rolls stuffed with hair. Bustles of this class have been heretofore made in which one or more 15 pockets or rolls are attached together by a flap or edge on one side of the roll or pocket somewhat in the manner in which the leaves of a book are secured therein, the said pockets or rolls having also divisions or partitions there- 20 in at right angles to the length thereof; and, further, bustles of this class have been made in which the rolls forming pockets are built into and form a part of the body or base and are an integral part of the bustle or fabric in 25 which the same are made or used.

The shape, form, and configuration given to the drapery of the person wearing bustles or other fabrics made in the manner just described depends entirely upon the shape of 30 the pattern used in cutting the material for the said pockets, rolls, or fabrics containing the same, and the manner in which the said patterns are laid upon the cloth or other material used in the making of the same, and no 35 satisfactory results have been attained in the configuration given in the drapery of the person wearing the bustle or other fabric or in the comfort and ease with which the same is thus worn.

40 The object of this invention is to provide a bustle which will not be open to the objections above noted; and to that end the invention consists in constructions and combinations, all as will be hereinafter described, and pointed 45 out in the claims, reference being had to the accompanying drawings, in which—

Figure 1 represents a perspective of my improved bustle, and Fig. 2 a vertical section of the same.

50 Like letters refer to like parts throughout the several views.

A represents the bustle, and B the waistband, which may be of the usual form, if desired. The bustle A is composed of the rolls *a*, *a'*, and *a''*, and the back *a''*, to which the rolls 55 are separately attached.

The rolls are approximately circular in cross-section, and the completed bustle is crescent-shaped in appearance, the rolls being of different sizes. The roll *a* is the smallest, and 60 presents its lower and outer surface to and rests upon or nearly upon the upper and inner surface of *a'*. Each of the rolls is provided with flaps *a⁴* and *a⁵*, by means of which it is attached to base *a''*. The ends *a⁶* of the 65 rolls are on substantially the same plane and in such a position that the belt B will cover the said ends and present a finished appearance. This is accomplished by doubling or folding the belt lengthwise and securing the 70 fold *b* upon the inner end or side of the bustle and the fold *b'* upon the outer side of the bustle. That part of the belt extending beyond the bustle may be sewed together to present the appearance of a single thickness. 75

By reference to the drawings it will be observed that back *a''* forms a foundation to which said rolls may be attached by means of flaps *a⁴* and *a⁵*, and any desired curve may thus readily be given to the upper side or surface 80 of rolls *a* *a'*, the back *a''* being a comparatively flat surface and holding said rolls in position.

By this construction I am able to present an outer surface to the bustle which will support the apparel in a proper and becoming manner. 85

Having described my invention, I claim as new—

As a new article of manufacture, a bustle 90 having a base extending underneath a series of rolls separately attached thereto by means or flaps on said rolls, with the ends of said rolls in the same plane, or nearly so, and covered or bound into a belt, together with said 95 base, all combined substantially as described, and for the purpose set forth.

EMMA E. HODSON.
